OIL BURNER

Lynn Otis Selby, Rocky Hill, Conn., assignor to
 The Sparmal Engineering Corporation, a corporation of Connecticut

Application August 2, 1937, Serial No. 156,989

20 Claims. (Cl. 158—28)

My invention relates to oil burners.

It has among its objects to provide an improved oil burner, and, more particularly, such a burner of the so-called power type, i. e. of the type requiring pressure to operate the same. A further object of my invention is to provide an improved power type burner having improved means for heating and vaporizing the oil and igniting the same and for supplying oil and air thereto, whereby more complete combustion of an increased amount of oil is obtained in such manner as to produce an exceedingly hot yet entirely clean flame and whereby the burner is adapted to intermittent operation in accordance with variations in demands for heat. Still another object of my invention is to provide an improved burner including a plurality of burners and wherein one of the burners is a preheating burner and constantly maintains the vaporizing means of the other at an operating temperature, and the other is intermittently operable in accordance with variations in demands for heat affecting associated control mechanism. A still further object of my invention is to provide an improved burner comprising an improved combination of a distillate burner with a power burner wherein the distillate burner can operate independently to contribute substantially to the heat output and wherein it also acts to vaporize and ignite the oil for the power burner in an improved manner maintaining the latter ready for operation at any time. Another object is to provide an improved construction wherein the two burners are coaxially arranged in an improved manner with the oil and air supplies for the power burner passing upward around the axis of the distillate burner in such manner that the burners may cooperate in the new and improved manner above described. A still further object of my invention is to provide an improved burner installation including the above described mechanism and having improved means for supplying oil to the distillate and power burners and supplying air to the two burners while controlling the air and oil supplies to both burners in accordance with the demands of the installation, the power burner being responsive to changes in temperature or pressure. These and other objects and advantages of my improved construction will, however, hereinafter more fully appear.

In the accompanying drawings, I have shown for purposes of illustration, three embodiments which my invention may assume in practice.

In these drawings—

Figure 1 is a diagrammatic view of a heating

installation equipped with one form of my improvement, a portion of the heater being broken away to show the burner in side elevation therein;

5 Fig. 2 is an enlarged view of the burner and its supply and control connections removed from the heater, the outer casing of the burner being broken away to show the shells of the distillate burner and the shells also being broken away to show the power burner disposed therein, while the casing containing the supply connections to both burners is also broken away to facilitate illustration;

15 Fig. 3 is an enlarged plan view of the burner base shown in Figure 2, the shells being removed to facilitate illustration and the casing and power burner tubes being in section on line 3—3 of Fig. 2;

20 Fig. 4 is a similarly enlarged vertical sectional view through the burner base, the sections being taken on line 4—4 of Figure 3 and the shells also being added;

25 Fig. 5 is an elevational view of a modified installation, herein a steam pressing installation equipped with my improvement, and

Fig. 6 is a perspective view of a modified form 30 of my improvement including oil and air connections for multiple burners, parts of only one of the distillate burners being shown, to facilitate illustration.

Referring to the construction shown in Figure 1, it will be noted that I have therein shown a heater 1 of any suitable type for heating air, hot water or steam, and having mounted in the fire box A therein above a usual false bottom or baffle 1a, a vertically delivering burner of my improved construction, generally indicated at B, this burner being of a type adapted to be automatically controlled through an electric control mechanism, such, for example, as a usual thermostat 2, acting to control the supply of liquid fuel from a storage reservoir 3 and air from a blower 4 to the power burner of the improved burner B, as hereinafter described.

45 Referring more particularly to Figures 2, 3 and 4, it will be noted that the burner B has an outer casing 5, herein having a usual bevelled removable top 6 and a lower axial upstanding neck 7. Coaxially disposed with respect to this neck and

50 within the casing 5 is a distillate burner, generally indicated at 8, and adapted as usual in such burners to have vaporized fuel supplied thereto and to develop high temperature, and herein comprising usual shells 9 and a base 10 having usual burner grooves 11 supplied from a

carbon leg 12. While not limited thereto, herein, this distillate burner is of the so-called Bunsen type shown in the Barhoff et al. Patent No. 2,020,867, the same being found to be well adapted to my purposes. However, it will be noted that herein the patented construction is modified and improved in certain respects to adapt it to be used in combination with my improved power burner. Herein, instead of having a central chamber, it will be noted that I provide an annular vapor distributing or so-called vaporizing chamber 13 to which the carbon leg 12 is herein connected at one side of the axis of the base 10 so that it may function in a usual manner in such distillate burners. Moreover, instead of having a cover plate which extends over the entire area of such a central upstanding chamber, I herein provide an axially apertured cover plate 14 which extends over my annular chamber while having the usual four extensions 15 which overlie the radial channels 13a extending from the annular chamber 13 into the next adjacent groove 11. Preferably, the radial channel 13a adjacent the carbon leg 12 is closed off, as shown in Figure 3, so that the vapor will not largely flow out through this adjacent channel but will be forced to flow more evenly to the next outer groove 11. Thus, when usual covers 14a are placed over the radial channels 13b between the two outermost grooves, it will be evident that a distillate burner construction is provided which is adapted to operate as such, while being adapted to receive my improved power burner disposed coaxially therewith and leading upward through the burner base and cover plate and within the innermost shell.

Referring more particularly to this power burner, it will be noted that an outer tubular member 16 extends up axially through this plate 14 and the bottom of the burner base 10 to a point substantially above the top of the latter, herein to a point above the shells as illustrated. Within this member 16 and spaced therefrom is also a like tubular member 17 of smaller diameter, herein, as preferably, terminating at substantially the top of the burner base. It will be noted that the tubes 16 and 17 are joined at their lower ends, as by a body of solder or brazing material 18 to form an annular vaporizing chamber 19 extending below the base 10 and closed at its lower end and which terminates within the outer tube 16 at the top of the tube 17. Preferably, the lower end 16a of tube 16 is formed of brass or other good heat conducting material so as to abstract heat readily from the base 10 of the distillate burner, and is screwed, welded or otherwise suitably fixed to the latter, all in such manner as further to facilitate heat transfer therefrom. The upper end 16b of the tube 16, which is above the burner base and is telescoped over the upper end of portion 16a, is, however, formed of a suitable alloy steel adapted to withstand high temperatures, as, for example, a very high chrome steel. It will be evident that the chamber 19 which is inside the tube 16 and surrounds the tube 17 provides, in effect, a vaporizing chamber or generator of large capacity.

The supply of oil to the carbon leg 12 of the distillate burner 8 and the chamber 19 of the power burner is herein separately controlled. Herein, the oil is supplied to the carbon leg 12 from the reservoir 3 by a pipe line 20 controlled by a usual safety valve 21 and, in turn, supplying oil to a usual float or constant level valve 22, the latter having a usual needle valve 23.

which, in turn, controls the supply of oil therefrom to a pipe line 24 which is connected to the bottom of the carbon leg 12. The oil for the power burner chamber 19 is herein also supplied from the reservoir 3 through the pipe line 20 and float valve 22, but controlled by a separate needle valve 25 controlling the flow through a pipe line 26 which opens into the chamber 19, herein at a point near the bottom thereof. Thus it will be evident that while oil may be supplied from a common reservoir to both burners, the same may be separately controlled by the different needle valves 23, 25 to vary the amount of flow as desired when the burners are operating, a larger amount ordinarily flowing to the power burner than to the distillate burner. It will, however, be understood that I contemplate the use of separate oil supplies for the two burners, if desired, it then only being necessary to provide a pair of float controlled valves each carrying a single needle valve and controlling the flow between its burner and a separate supply line or tank, such a construction making it possible to supply oil of different quality to the different burners whenever desired.

Operatively associated with the tube 17 is improved air supply means. Herein an elbow 27 is suitably connected as by threading or brazing on the lower end of the pipe 16 surrounding the welded or brazed connection between the pipes 16 and 17, and this elbow is, in turn, connected with a horizontally disposed air supply pipe 28 which is herein connected to any suitable blower, herein an electric motor driven blower 29 of the well known "Sirocco" type and having a suitable adjustable air inlet 29a. Thus it will be evident that when this blower is operating, air will be supplied therefrom through the pipe 28 and up through the elbow 27 and through the inner pipe 17 in such manner as to draw up the vapor in the power burner vaporizing chamber 19 and cause said vapor to be ignited by the flame of the distillate burner and burn above the top of the pipe 17, the base of the flame being above and adjacent the top of air supply pipe 17 where the vapor from chamber 19 first mixes with the air issuing from this pipe.

In a preferred construction, a suitable baffle is disposed in the bottom of the top portion 16b of the pipe 16 and above the upper end of the pipe 17, this baffle being adapted to direct the rising vapor into the path of the upwardly directed air stream and being herein in the form of an axially apertured ring 30. Obviously, however, baffles of various other forms may be utilized to produce this effect. Here attention is also directed to the fact that I also herein provide an outer casing 31 connected to the lower end of the neck 7 and enclosing the air supply 28 and the oil pipes 24 and 26 between the blower 29 and the neck, in such manner as to protect the various supply lines and produce a rugged structure. Herein, an adjustable inlet or damper 10a is provided in the side of this casing 31 to provide a controllable air supply to the usual air apertures 10b in the burner base 10. Attention is further directed to the fact that this casing 31 is herein mounted on a three-point support including a single point vertically adjustable front support 32, herein depending from and supporting the elbow 27, and two rear vertically adjustable single point supports 33. As a result of this construction and suitable adjustment of these supports 32, 33, it is made possible not only to control the vertical position of the burn-

er base 10, but to level the same in intersecting planes.

Operatively associated with the mechanism thus far described, is electric controlling mechanism, herein adapted to be controlled by the thermostat 2 and controlling the motor driving the blower 29 and the supply of oil through the pipe line 26 to the power burner 19. More particularly, current flows from the line 34 to a usual relay 35 controlled by the thermostat 2, and flows from this relay to the motor, generally indicated at 36, through conductors 37, while conductors 38, connected in parallel to the conductors 37, lead to a suitable controlling valve 39 preferably of a usual solenoid type adapted to control the flow through the pipe line 26 and also preferably disposed within the casing 31. As a result of this construction and due, it is believed, to the delay inherent in bringing the motor 36 up to speed, the solenoid valve 39 is first operated when current flows simultaneously through the lines 37, 38, in such manner as to insure that oil will be supplied to the power burner chamber 19 before the motor 36 reaches its normal operating speed.

In the operation of my improved construction, it will be understood that the distillate burner 8 is first started in a usual manner and that this burner continues to operate, preferably at a constant flame determined by the setting of the needle valve 23, throughout the operation of the device, the damper 10a of course being adjusted as needed. When this burner has been operating sufficiently long, it brings the burner base 10 and the part of tubular member 16 forming the outer wall of the power burner vaporizing chamber 19, to a proper temperature, i. e. to such temperature as to vaporize oil in that chamber and cause vapor to rise therefrom by its own heat and in such manner as to act to prevent the entry of air into the vaporizing chamber, while the vapor passes in the form of unburned gaseous vapor into the combustion chamber. With the vaporizing chamber 19 thus heated, it will be evident that the power burner will be started automatically whenever oil is supplied through the line 26 into the chamber 19 and the blower 29 is started. In practice, the distillate burner 8 brings the tube 16 to a sufficiently high temperature that the power burner may thus be started within ten to twenty minutes after starting the distillate burner. Attention here is further directed to the fact that with the pipe 16 at high temperature, the oil in the chamber 19 between this pipe and the air pipe 17 is very completely vaporized as described above and is also sucked up along the outside of the pipe 17 by the air stream and into the path of the air flowing from the blower through the pipe 28 and pipe 17 as heretofore described; the baffle ring 30 also assisting in obtaining an effective mixture of the air and gas and directing the flame up through the combustion chamber. In practice, it is found that the flame burning at the upper end of the pipe 17, as heretofore described, and extending above the upper end of the pipe 16 may operate over long periods without any evidences of carbonization, while the flame is of an extraordinary white-blue character, white toward its top and above the pipe 16b, and blue within the tube 16 further indicating complete combustion. Attention is also directed to the fact that the white flame indicates the production of an intense radiant heat in that portion of the flame where such heat

is most useful, i. e. in the heater fire box, while the blue flame, being in the tube 16, is disposed in the most effective heat conducting relation for such a blue flame with respect to the vaporizing and combustion chambers. Obviously, when the power burner has once been started, it will continue to operate under the control of the thermostat 2 in a well known manner, the motor 36 for the blower 29 being stopped and started in accordance with changes in temperature acting upon the thermostat; the heated base 10 and tube 16, due to the continuously operating distillate burner, acting to maintain the chamber 19 at vaporizing temperature in such manner as to insure immediate starting of the power burner whenever oil and air are supplied thereto. In this connection, attention is also directed to the fact that with the tube 16 thus maintained at a high temperature by the distillate burner, the power burner can either start or stop in accordance with temperature requirements of thermostat 2 and with a minimum of smoking.

In Figure 5 I have illustrated a modified form of installation. In this figure, I have shown an improved burner of the same general character as that heretofore described, used in connection with any suitable steam boiler 40 of the vertical tube type usual in connection with a steam presser, the latter including a usual stationary pressing element 41 and a movable cooperating pressing element 42 which is controlled by usual control mechanism operated by a foot lever 43. With steam supplied from the boil 40 to heat the cooperating pressing elements 41 and 42 and the operation of the latter and the steam supplied thereto, being controlled by the foot lever 43 in a well known manner, it is found that my improved burner will supply sufficient steam to enable continuous operation of the pressing machine while very substantially reducing the cost of operation of such machines, heretofore operated by coal or gas. In fact, with my improved burner connected to such a boiler 40, it is possible to operate a plurality of pressing machines from a single boiler while at the same time substantially reducing the heating expense. Here obviously, as usual in boilers, a pressure responsive control (not shown) will be used in place of the temperature responsive mechanism heretofore described.

In Figure 6, I have illustrated a further modified construction wherein while utilizing my improved burners, a plurality of the same may be connected to a single air supply line 44. Here it will be understood that the distillate burners, parts of only one of which are illustrated, are each of the same construction heretofore described in connection with Figures 2 to 4, so that a further description thereof is unnecessary. However, it will be noted that, as in a preferred construction, the connections between the air supply 44 and the several tubes 16, on which the burner bases are carried as heretofore, include connections 45, 46 so constructed and arranged that the connections to the several tubes from the common air supply are of equal length in such manner as to insure uniform operation of all the burners. Here of course, it will be understood that while only an air supply has been shown in this figure, oil and air supplies similar to those heretofore described in connection with Figures 2 to 4 and similarly controlled, are also provided, while the member 44 is also enclosed in an adjustably mounted casing similar to the

casing 31. It will also be understood that while only three such burners have been shown, I contemplate the use of two, four, or as many as may be desired, arranged in such a cluster as shown, or in alignment, while I further contemplate the use of one or more of these burners either in connection with a single boiler or in connection with a series of boilers.

As a result of my improved construction, it is made possible to obtain wholly new results as regards maximum temperature from a power burner, temperature tests indicating that the flame produced by my improved burner is substantially hotter than that obtained by any other power burner of which I am advised. This is believed to be due to an improved and more complete vaporization and resultant more complete combustion, resulting from my improved construction. Attention is further directed to the fact that these results are obtained without requiring an intermittently operated supplementary burner, the distillate burner in my improved construction operating continuously and without necessity for manual throttling or other attention on the part of the operator, than the starting operation and the setting of the needle valve and damper to insure continued operation at the desired rate of oil and air flow. Further, it will be noted that these results are obtained without requiring any supply of oil under pressure to the power burner, the oil instead being supplied by gravity from the reservoir, and, moreover, being vaporized completely in the power burner chamber 19 before it is ignited, as distinguished from as heretofore being sprayed into the air stream or otherwise picked up by the air stream and supplied in globules of cold oil directly into a combustion chamber. As compared with prior power burners having a stationary oil delivery, attention is also particularly directed to the fact that while obtaining the above advantages, I am also able to produce a power burner which is free from objectionable roar in operation, this being believed to be due to the use of my improved power burner structure and in part also to the use of an air supply which is of substantially the same diameter, and preferably a substantial diameter, from the blower to the outlet inside the pipe 16 and also to the provision of the ring 30. Here also it will be noted that due to the use of gravity and the constant level valve 22 in the oil supply to the distillate and power burners, it is made possible to produce an exceedingly safe construction wherein the oil levels may not exceed the limits set under the most strict municipal regulations, all danger of flooding thus being effectually avoided even should the burner go out for any reason, as, for example, upon failure of the oil supply. Attention is further directed to the marked flexibility of the same in operation in accordance with temperature, or hot water or steam requirements, it being possible in my improved construction to vary the oil consumption by the power burner, as desired, by adjusting the needle valve to any selected point between the limits thereof, without affecting the heating character of the power burner flame or causing the latter to smoke and carbonize the burner and fire box. Attention is also directed to the simplicity of the construction, as well as to the long wearing qualities of the structure, all need for high pressure pumps and ignition mechanism being eliminated and the only moving parts, apart from the relay, being the simple motor driven blower and the

trouble free solenoid and float valves. Thus, when the pipe 16 is made of a suitable alloy adapted to withstand the high heat, the mechanism is adapted to function indefinitely without attention other than ordinary service requirements in connection with the thermostatic control of the same. Attention is also particularly directed to the markedly reduced manufacturing cost and the reduced operating and maintenance expense of my improved mechanism. These and other advantages of my improved construction will, however, be clearly apparent to those skilled in the art.

While I have herein specifically described three embodiments which my invention may assume in practice, it will be understood that these forms are shown for purposes of illustration, and that my invention may be modified and embodied in various other forms without departing from its spirit or the scope of the appended claims.

What I claim as new and desire to secure by Letters Patent is:

1. In combination, a burner having vaporizing means and oil supply means therefor, means for delivering air under pressure entraining the vapor as it emerges from said vaporizing means, a combustion chamber for the combustible mixture above said vaporizing and delivering means and receiving air and vapor therefrom, mechanism for conditioning the burner for starting including means for heating said vaporizing means to a vaporizing temperature and for effecting ignition of the combustible mixture, and means controlling the supplies of air and oil for starting and stopping said burner.

2. A power burner having pressure air and oil passage means, and having a vaporizing chamber supplied from said oil passage means having an upwardly directed outlet, and means for maintaining said chamber sufficiently heated to vaporize oil in said chamber throughout the operation of the burner, and said burner also having a combustion chamber above and communicating with said vaporizing chamber, the air supply means delivering air adjacent the outlet of the vaporizing chamber and entraining the vapor as it emerges from said vaporizing chamber and said air supply means discharging sufficient air into said combustion chamber to maintain combustion therein.

3. A power burner having pressure air and oil passage means therein, and having a vaporizing chamber supplied from said oil passage means and disposed out of the path of the air supply, means for heating said chamber to vaporize liquid oil supplied thereto by said oil passage means throughout the operation of the burner, and means forming a combustion chamber having an outlet delivering to a point remote from said vaporizing chamber and communicating with said vaporizing chamber, said air supply means delivering air entraining the vapor as it rises from said vaporizing chamber to form a combustible mixture burning in said combustion chamber and said air blowing the flame from the outlet of said vaporizing chamber through said combustion chamber.

4. In combination, heating means, a burner having vaporizing means maintained at a vaporizing temperature by the heat of said heating means throughout the operation of the burner and also an upwardly opening combustion chamber above and communicating with said vaporizing means at a point inside said burner and having an outlet at its top delivering at a point re-

mote from said vaporizing means, means for supplying fuel to said vaporizing means, and means for supplying air under pressure through said vaporizing means into said chamber for entraining the vapor as it emerges from said vaporizing means and delivering the combustible mixture to said combustion chamber.

5. In combination, heating means, a burner having vaporizing means maintained at a vaporizing temperature throughout the operation of the burner by the heat of said heating means, and a chamber in said burner communicating with said vaporizing means and having fuel and air mixing means within said chamber, means for supplying fuel to said vaporizing means, and means for supplying air under pressure to said chamber including an air supply passage forming means extending through said vaporizing means into said chamber and discharging air entraining and forming a combustible mixture with said vapor as said vapor emerges from said vaporizing means into said chamber.

6. In combination, combined heating and igniting means, a burner having vaporizing means heated by said means to constantly maintain the burner in condition for starting, said burner also having passage forming means for delivering oil to said vaporizing means and passage forming means for delivering air under pressure for entraining the vapor as it emerges from said vaporizing means and also mixing the air and vapor and delivering the mixture for ignition by said heating and igniting means, and mechanism for starting and stopping the burner including devices for establishing and interrupting delivery of air and oil through said air and oil passage forming means.

7. A power burner having pressure air and oil passage means, a vaporizing chamber surrounding said pressure air passage means and receiving oil from said oil passage means and having an outlet at its top so disposed that the vapor generated in said chamber will rise under its own heat through said outlet, and said burner also having an upper chamber positioned to receive vapor rising from said vaporizing chamber and having a constriction above and adjacent the outlet of the latter, and means for maintaining said vaporizing chamber throughout operation of said burner at a sufficiently high temperature to effect vaporization of oil supplied thereto, said air passage means supplying air under pressure to said upper chamber to effect entraining of the rising unburned vapor with said air supply as said vapor emerges from said vaporizing chamber into said upper chamber to form an ignitable mixture burning in the latter.

8. A power burner having pressure air and oil passage means therein and having a vaporizing chamber surrounding said air passage means and adapted to be heated to vaporize oil in said chamber, and also having a mixing and initial combustion chamber communicating with said vaporizing chamber at the top of the latter and in which burning takes place, the air from said air passage means entraining the vapor as it emerges from said vaporizing chamber to form a combustible mixture in said chamber and said air passage means discharging an air stream blowing the flame upwardly in said combustion chamber, and vapor flow directing baffle means in said chamber directing the vapor into the path of the moving air stream.

9. In combination, a power burner having a mixing and initial combustion chamber and va-

porizing means of substantially smaller cross sectional area than the adjacent portion of said chamber and delivering into the latter, means responsive to demands for more or less heat for delivering or stopping delivery of both fuel to said vaporizing means and air under pressure entraining and forming a combustible mixture in said combustion chamber of said air and the vapor rising from said vaporizing means into the air stream, and heating means for constantly maintaining said vaporizing means at an operating vaporizing temperature ready to start said power burner upon delivery of fuel and air as aforesaid.

10. In combination, a combustion chamber having an upwardly directed outlet delivering a flame upwardly into a fire box, a vaporizing chamber having oil heating and vaporizing passage forming means adjacent and disposed beneath and communicating with said combustion chamber, means for supplying air under pressure for entraining gaseous vapor emerging from between said passage forming means and for blowing flame from adjacent said vaporizing chamber through said combustion chamber, means for so heating said passage forming means throughout the operation of the burner as to vaporize oil therein and cause gaseous vapor to rise and emerge from said vaporizing means to form a combustible mixture with the air stream, and means located in said combustion chamber between the outlet thereof and the upper ends of said vaporizing chamber and air supply means for mixing the air and vapor into a combustible mixture.

11. In combination, an annular preheating burner including a burner base, a power burner connected to said base and having a vaporizing chamber extending centrally through and preheated by said annular burner and said power burner delivering flame upwardly within the flame of said annular burner, means for supplying oil to said preheating burner, and means for intermittently supplying both air and oil to said power burner to start and stop the latter while said preheating burner is operating.

12. In combination, an outer burner, and a power burner coaxial therewith and delivering through and preheated by said first mentioned burner and having upwardly directed pressure air supply means and a coaxially disposed fuel vaporizing chamber for said power burner, and having said chamber heated by said outer burner and disposed out of the path of the air supply, and an upwardly opening chamber coaxial with and above said vaporizing chamber into which said air supply means discharges air and into which said vaporizing chamber discharges vaporized fuel.

13. In combination, a constantly operating outer burner delivering flame upwardly and having means for delivering vaporized oil thereto, and a cooperating power burner centrally disposed with respect to and preheated by said first mentioned burner and having vertical pressure air passage means in said power burner and a coaxially disposed fuel vaporizing chamber in said power burner and also having means forming a combustion chamber in said power burner above said air passage means in which the vapor from said vaporizing chamber is burned for directing a flame upwardly with respect to said vaporizing chamber centrally within the flame of said first mentioned burner.

14. In combination, a burner having means for

delivering vaporized oil thereto and also including coaxial perforated shells defining combustion spaces, and a power burner preheated by said first mentioned burner and having vertical pressure air passage means in said power burner and a coaxially disposed fuel vaporizing chamber in said power burner, said power burner being disposed coaxial with respect to said shells and also having a combustion chamber above said vaporizing chamber and in which vapor rising therefrom is burned and also having said combustion chamber extending upwardly within said shells and delivering the flame upward with respect to said vaporizing chamber.

15. In combination, a substantially annular constantly operating burner having means for supplying vaporized oil thereto and including an eccentrically disposed fuel supply connection and a central aperture, and a power burner in said aperture centrally disposed relative to said first mentioned burner and preheated by said first mentioned burner and having vertical air passage means and a fuel vaporizing chamber for said power burner coaxially disposed relative to said aperture, and a combustion chamber above said vaporizing chamber in which the mixture of air and fuel supplied to said combustion chamber is burned and having an outlet delivering the flame upwardly from said vaporizing chamber.

16. In combination, a burner having vaporizing means for supplying vaporized oil thereto, a power burner preheated by said first mentioned burner and having vertical air supply means and a fuel vaporizing chamber, and also having a central chamber in which partial combustion of said air and fuel takes place above said vaporizing chamber, said first mentioned burner having vapor conducting grooves surrounding said vaporizing chamber and the latter having its bottom disposed below the bottoms of said grooves, and a constant level fuel supply means common to both burners having fuel supply connections to said vaporizing means and to said vaporizing chamber.

17. In combination, a pair of cooperating burners including a power burner having an annular vaporizer and upwardly directed communicating air and flame passage forming means in said power burner coaxial with said vaporizer and a cooperating preheating burner having annular combustion chamber forming means relative to which said vaporizer is centrally disposed, and a burner base connected to said vaporizer and supporting said combustion chamber forming means and through which base said air passage forming

means supplies air axially under pressure to said flame passage forming means.

18. In combination, an outer burner having vaporizer means for vaporizing oil supplied thereto and communicating upwardly directed combustion chamber forming means, and a cooperating power burner within and preheated by said first mentioned burner and delivering flame in the same direction as said first mentioned burner and comprising coaxially disposed pressure air and oil passage means, a vaporizing chamber above and communicating with said oil passage means, and also comprising a combustion chamber communicating with said vaporizing chamber and of substantially greater cross sectional area than said vaporizing chamber in the portion of said combustion chamber adjacent said vaporizing chamber and above the latter and said air passage means.

19. In combination, a preheating burner having vaporizing means and annular perforate shells disposed in vapor conducting grooves communicating with said vaporizing means, and a power burner extending centrally through said preheating burner, said power burner having a vaporizing chamber heated by said preheating burner and a pair of coaxially disposed tubular elements providing passages for pressure air and combustion products, one delivering pressure air for entraining and delivering for burning in said power burner the vapor rising from the vaporizing chamber of said power burner and the other carrying away the products of combustion from within said power burner.

20. In combination, a pair of cooperating distillate and power burners one within the other and each having vaporizing means and each having coaxial upwardly directed flame delivering means and said delivering means in said power burner having a bottom portion of greater cross sectional area than the vaporizing means of said power burner, said distillate burner being so disposed as to heat the vaporizing means of said power burner and thereby maintain said vaporizing means ready to start said power burner in full operation upon delivery of oil to the vaporizing means thereof and air to mix with the rising vapor for burning within said flame delivering means of said power burner, and mechanism controlled by demands for more or less heat including intermittently operating starting and stopping means for supplying oil and air under pressure to cooperate with the vaporizing means of said power burner.

LYNN OTIS SELBY.
